Patented Nov. 9, 1965

202,845

UPDRAFT CARBURETOR

Clifford T. Philippert, Detroit, and Frederick J. Marsee,
Hazel Park, Mich., assignors to Holley Carburetor
Company, Warren, Mich., a corporation of Michigan

Filed Nov. 16, 1964, Ser. No. 82,617

Term of patent 14 years

(Cl. D77—1)

FIG. 1

Des. 202,845

PAGE 2

FIG. 2

Des. 202,845

PAGE 3

FIG. 3

FIG. 4

FIGURE 1 is a perspective view of one side of an updraft carburetor embodying our new design;

FIGURE 2 is a perspective view of the carburetor shown in FIGURE 1, but taken from the opposite side thereof; and

FIGURES 3 and 4 are additional perspective views, both taken from the bottom but at opposite ends of the carburetor.

We claim:

The ornamental design for an updraft carburetor, substantially as shown and described.
